(57) **CLAIM**

The ornamental design for a bearing set for crushers, as shown and described.

DESCRIPTION

FIG. 1 is a first perspective view of a bearing set for crushers showing our design taken from a right side and above a horizon, the bearing set being sold as a set inclusive of a main shaft component, a piston wearing plate component, and a step washer component;

FIG. 2 is a second perspective view thereof taken from the right side and below a horizon;

FIG. 3 is a left side view thereof;

FIG. 4 is a top view of the main shaft component of the bearing set;

FIG. 5 is a bottom view thereof;

FIG. 6 is a left side view thereof;

FIG. 7 is a rear view thereof;

FIG. 8 is a right side view thereof;

FIG. 9 is a front view thereof;

FIG. 10 is a top view of the piston wearing plate component of the bearing set;

FIG. 11 is a bottom view thereof;

FIG. 12 is a rear view thereof, left and right side views being the same;

FIG. 13 is a front view thereof;

FIG. 14 is a top view of the step washer component of the bearing set;

FIG. 15 is a bottom view thereof;

FIG. 16 is a right side view thereof, the left side view being the same; and,

FIG. 17 is a front view thereof, the rear view being the same.
